UNITED STATES PATENT OFFICE.

GEORGE O. WALKER, OF WALKER, OREGON.

DRAG-SAW MACHINE.

SPECIFICATION forming part of Letters Patent No. 781,700, dated February 7, 1905.

Application filed October 14, 1904. Serial No. 228,461.

To all whom it may concern:

Be it known that I, GEORGE O. WALKER, a citizen of the United States, residing at Walker, county of Lane, and State of Oregon, have 5 invented certain new and useful Improvements in Drag-Saw Machines, of which the following is a specification.

This invention relates to portable drag-saw machines, and more particularly to the apparatus for operating them.

Heretofore in sawing a log after it has fallen from the stump it has been necessary to move the power or engine with the portable drag-saw as the latter is moved along the length of 15 the log to make the successive cuts which saw up the log into short blocks.

The object of the present invention is to provide novel means for operating the portable drag-saw from the engine or power so 20 that the power may remain stationary at all times, though the drag-saw is moved lengthwise of the log to make the successive cuts; and the invention also aims to provide an improved arrangement of pulleys or sheaves on 25 the drag-saw to effect this object.

The invention consists in the novel features and combinations appearing more fully hereinafter and recited in the appended claims.

In the accompanying drawings, Figure 1 is 30 a plan view illustrating the apparatus and its manner of use; Fig. 2, a rear view looking toward the log; Fig. 3, a rear elevation of the machine; Fig. 4, a detail plan view of the improved pulley arrangement.

35 Referring first to Figs 3 and 4, the machine has a four-wheeled truck 1, which carries a frame 2, in the upper part of which is journaled a large cable-sheave 3, whose plane extends transversely of the truck. The drag-saw 3' may be mounted in the usual manner, so as 40 to fall as the saw-cut deepens, and operated from sheave 3 by crank 3", pitman 3'", and clutch 2'. Journaled on stub-shafts 4 and 5, secured to the frame 2 at the lower and side 45 portion thereof, are small sheaves 6 and 7, the former lying at an angle nearly approximating the "vertical" and the latter being disposed in a plane nearly approximating the "horizontal," it being understood that these

sheaves are tangentially disposed relative to 50 the sheave 3.

Reference being had to Figs. 1 and 2, the manner of use of the invention will be understood. The numeral 8 represents the fallen log cut from the stump 9 and which it is desired to saw up into short blocks. The traction-engine or other "power" 10 is stationed adjacent one end of the log 8, and a vertical sheave 11 is mounted on any suitable support 12, (at the time of sawing or previously 60 on a regular standard.) A cable 13 is then passed around the drum 14 of the engine 10 and one strand led direct to sheave 11. The balance of the cable is then passed around sheaves 6 and 7 and around sheave 3. The 65 rotation of drum 14 turns sheave 3 and reciprocates the drag-saw 3'. After the cut has been made the truck 1 is wheeled to another position, (the engine 10 meanwhile remaining in its former position,) as shown by dotted 70 lines, Fig. 1, without stopping the engine 10 and positioned where desired to make the succeeding cut, this method of sawing being carried on, starting with one end of the log, until the entire log is sawed up into short blocks. 75

A very great saving of time and labor is obtained by using my apparatus for operating the drag-saw, as in the old way the engine has to be moved each time the drag-saw is moved to make a succeeding cut.

Having thus described my invention, what I claim as new, and desire to secure by Letters Patent, is—

1. A portable sawing-machine mounted to travel in a line substantially at right angles 85 to the cutting plane of the saw to make successive cuts, and comprising a saw, and a saw-operating sheave, in combination with two sheaves and means for power-driving one of them, and an operating-cable passing about 90 such sheaves, said cable being arranged in a line substantially parallel to the path in which the sawing-machine is adapted to travel to make successive cuts, and said cable being carried around the saw-operating sheaves. 95

2. A portable sawing-machine mounted to travel in a line substantially at right angles to the cutting plane of the saw to make suc-

cessive cuts, and comprising a saw, and a saw-operating sheave, in combination with two sheaves and means for power-driving one of them, an operating-cable passing about 5 such sheaves, guide-sheaves placed adjacent the saw-operating sheave to change the plane of the cable as it passes to and from said saw-operating sheave, said cable being arranged in a line parallel to the path in which the saw-

ing-machine is adapted to travel to make successive cuts, and said cable being carried around the saw-operating sheave. ¹⁰

In testimony whereof I hereunto affix my signature in presence of two witnesses.

GEORGE O. WALKER.
